UNITED STATES PATENT OFFICE.

WALTER H. BELL, OF DAYTON, OHIO, ASSIGNOR, BY MESNE ASSIGNMENTS,
TO NATIONAL CASH REGISTER COMPANY, OF JERSEY CITY, NEW JERSEY,
A CORPORATION OF NEW JERSEY.

CASH-REGISTER.

SPECIFICATION forming part of Letters Patent No. 705,552, dated July 29, 1902.

Application filed July 30, 1898. Serial No. 687,251. (No model.)

To all whom it may concern:

Be it known that I, WALTER H. BELL, a citizen of the United States, residing at Dayton, in the county of Montgomery and State of 5 Ohio, have invented certain new and useful Improvements in Cash-Registers, of which I declare the following to be a full, clear, and exact description.

This invention relates to improvements in 10 cash-registers, and has more particular relation to improvements in machines of the type patented to Thomas Carney, No. 536,015, dated March 19, 1895.

The primary object of the invention is to 15 provide in a machine of the class mentioned an improved flash or guard for the indicating-tablets to prevent them from becoming visible until after the registration has been completed, and thus avoid any possibility of 20 fraudulent operation of the machine.

In the appended drawings, forming part of this specification, Figure 1 represents a vertical transverse section through a machine of the class mentioned with my invention applied thereto, and Fig. 2 represents a top plan view of the same.

In the said drawings, 1 represents the frame of the machine; 2, the operating-keys; 3, the key-coupler, and 4 the indicator-tablets for 30 said keys. The keys, key-coupler, registering mechanism, and indicators are of substantially the same construction and operation as those described in the said patent, and attention is therefore called to the same for a detail description of the parts. The key-coupler 3, which is adapted to be elevated upon the operation of any of the keys, as fully described in the aforesaid patent, is arranged to 35 operate two arms 5, pivotally mounted upon each end of the key-shaft 5^a. Each of these arms is formed with a hook end 5^b, similar to the hook ends of the regular keys, with the exception that their hook extensions are of such length as to always project above the 40 key-coupler, and thus become coupled to the same every time that said coupler is operated. These arms 5 are adapted to coöperate with vertical spring-pressed rods 6, similar to the 45 regular tablet-indicator rods, to raise the same when the coupler is elevated and allow the

same to descend under the action of their springs when the coupler is lowered. It will be seen from the above that the said rods 6 are not held in their elevated positions upon the descent of the key-coupler, as are the 55 regular tablet-indicator rods, but descend with said coupler under the action of their respective springs. Each of these rods is provided at its upper end with a yoke 7, the two arms of which extend, respectively, to the opposite sides of the bank of regular tablet-indicators. Flash or guard plates 8 connect the arms of one yoke to those of the other and are located, respectively, in vertical planes to each side of the bank of tablet-indicators, so 60 as to hide the latter when the two are raised together.

It will be observed from the above that when a key is operated its indicator is raised into exposed position, but as the flash-plates 8 are 65 correspondingly raised it does not become exposed to view until the key is allowed to assume its normal position, and thus permit the key-coupler and the guard supported thereby to also descend. The said guard-plates pref- 70 erably contain words such as "Sale not registered," "No sale," or "No record," so that the customer will know that the machine is being fraudulently operated unless said guard drops down out of sight and exposes the 75 amount or other indicator-tablet. As long as the guard remains visible the indicators are concealed and the customer knows that the sale has not been registered; but when the guard has dropped sufficiently to expose the 80 said indicators the registration has been completed and the period where fraudulent operation may have been accomplished is past.

Having thus described my invention, what I claim as new, and desire to secure by Letters 85 Patent, is—

1. In a cash-register, the combination with a series of keys, of a series of indicators, a key-coupler, two movable yokes and connections coöperating with the key-coupler so as to 90 be simultaneously moved thereby and guard- 95 plates connecting the arms of said yokes so as to extend up on both sides of the indicators to conceal the same until the operation of the keys is completed.

2. In a cash-register, the combination with a series of keys, of a series of indicators, a frame arranged to be operated by any one of said keys, levers pivoted independently of said frame but arranged to be engaged and positively operated by the same in both directions, and an indicator-guard mounted independently of said levers but arranged to be operated by the same.
- 10 3. In a cash-register, the combination with a series of operating-keys, of a key-coupler coöperating therewith, indicators, pivoted levers mounted independently of the coupler but connected thereto so as to move positively therewith and a flash arranged to be operated by said levers to hide the said indicators while the keys are being operated.
- 15 4. In a cash-register, the combination with a series of operating-keys, of a key-coupler arranged to engage and hold said keys to simultaneous movement, a series of indicators,
- 5 an indicator-flash arranged to hide both sides of said indicators during the operation of the keys, and pivoted levers for operating said flash mounted independently of the coupler but coupled thereto so as to be moved positively therewith in both directions.
- 20 5. In a cash-register the combination with a series of operating-keys, of a series of indicators for said keys, a movable frame arranged to be coupled to said keys, two movable yokes coöperating with said frame and guard - plates connecting the arms of said yokes so as to extend both in front and back of the indicators and hide the same during the operation of the keys.
- 25 30 In testimony whereof I affix my signature in the presence of two witnesses.
- WALTER H. BELL.
